UNITED STATES PATENT OFFICE.

WILLIAM E. SHEEHAN, OF ALBANY, NEW YORK.

PAPER-MAKING MACHINE

1,150,636.

Specification of Letters Patent. Patented Aug. 17, 1915.

Application filed April 28, 1913. Serial No. 763,950.

To all whom it may concern:

Be it known that I, WILLIAM E. SHEEHAN, a citizen of the United States of America, residing at the city of Albany, in the county 5 of Albany and State of New York, have invented certain new and useful Improvements in Paper-Making Machines, of which the following is a specification.

My invention relates to paper making 10 machines and paper making processes, and the object of my invention is to provide a process and means for separating and preventing the adhesion of the plastic paper or pulp to the covering of the roll.

15 I accomplish this object as hereinafter described and illustrated.

Figure 1 is a section of a roll provided with a means for separating and preventing the adhesion of the plastic paper to the roll.

20 Fig. 2 is a section of a modified means for performing the result attained in Fig. 1.

Fig. 3 is an end elevation of a modified form

with part broken away.

Similar letters refer to similar parts 25 throughout the several views.

As the plastic paper is carried along and comes in contact with the roll in a paper making machine, its natural tendency is to stick thereto and be carried around with it 30 which occasions a great loss of time in removing the adhering mass.

My process comprises passing a continuous plastic sheet of paper between coverings on perforated rolls; said coverings 35 made of closely fitted, homogeneous fibrous material, and then forcing air through the under surface of the coverings on the rolls, destroying any force of suction or adhesion 40 which may be exerted on the paper by the centrifugal motion of the said rolls and forming an air cushion between the paper and the said coverings on the rolls.

I may accomplish this object by providing the roll, A, with the perforations, E, 45 as shown in Fig. 1, the roll being suitably mounted in the trunnions, B, and having a pipe, C, provided with a flaring nozzle, D, adapted to extend beneath a portion of the inner surface of the roll, so that the air 50 blown through the pipe will escape through the perforations, E, and be diffused through the fibrous covering, F. I show a pump, P, for forcing the air through the pipe, C.

In Fig. 2, I show another means for de-

livering the air to the surface of the roll. 55 I place in the roll, G, which is covered with felt or other fibrous material, H, a series of chambers, J, J, extending beneath the surface of the roll from one end, a, thereof to nearly the opposite end and providing a series of perforations, h, through the roll 60 communicating with the chambers, J, J, respectively. At one end, a, of the roll and mounted on the trunnion, K, which carries the roll, I place a fitting, L, provided with a 65 chamber, M, adapted to communicate with the chambers, J, J, when it registers with such chambers during the revolution of the roll. The fitting, L, revolves with the roll. Around the periphery of the fitting, L, I 70 place a ring, N, provided with an enlarged portion, S, in which enlarged portion there is a chamber, T, the chamber, T, being opened toward the periphery of the ring, N. The pipe, O, screwed into the enlarged 75 portion, S, of the ring, N, carries air from the pump to the chamber, T; from thence it passes into the chambers, J, J, in the roll. The ring, N, is stationary.

The fibrous covering, E, extends entirely 80 around and in close contact with the roll, providing a continuous fibrous surface with which the endless plastic web of paper engages. This roll is used as a press roll and when the air is forced or diffused through 85 the covering, there is formed an air cushion between the plastic material and the covering which renders the removal of the plastic material easy and prevents the breaking of the plastic web, and also prevents taking out 90 the pigments or minute fibrous material which otherwise would stick to the roll.

What I claim as my invention and desire to secure by Letters Patent is:

1. In a paper making machine, a hollow 95 perforated roll; a homogeneous fibrous material closely covering and extending entirely around said roll; and means for conducting to and discharging a current of air through the perforations in the roll into 100 and through the fibrous material and brought in contact with the plastic paper.

2. A process comprising passing a continuous plastic sheet of paper between closely fitting, homogeneous fibrous coverings on 105 perforated rolls, then forcing air through the coverings, destroying any force of suction or adhesion exerted on the paper by the

centrifugal motion of the rolls and forming an air cushion between the paper and said coverings.

3. A process of separating and preventing the adhesion of an endless plastic web of paper to the homogeneous fibrous material closely covering the press roll of a paper making machine, comprising the delivery of a current of air into and through the fibrous

material covering the roll and forming an air cushion between the said fibrous material and the web.

In testimony whereof I have affixed my signature in presence of two witnesses.

WILLIAM E. SHEEHAN.
